CLAIM

We claim the ornamental design for a port replicator, as shown and described.

DESCRIPTION

FIG. 1 is a front perspective view of a port replicator of the present invention;

FIG. 2 is a front view;

FIG. 3 is a rear view;

FIG. 4 is a left side;

FIG. 5 is a right side view;

FIG. 6 is a top view;

FIG. 7 is a bottom view; and,

FIG. 8 is an enlarged view of a portion of between 8-8 in FIG. 1.

The broken line showing of port replicator is included for the purpose of illustrating environment and forms no part of the claimed design. Additionally, the unevenly broken lines in the drawings define the limits of the claimed design.
